(57) **CLAIM**

The ornamental design for a gas range knob, as shown and described.

DESCRIPTION

FIG. 1 is a perspective view of a gas range knob showing our new design;

FIG. 2 is a front view thereof;

FIG. 3 is a top view thereof; and,

FIG. 4 is a side view thereof.

The bottom view is not shown and does not form a part of the claimed design.

The broken lines form no part of the claimed design.

The dotted lines represent the border between claimed and unclaimed subject matter and do not form a part of the claimed design.
